UNITED STATES PATENT OFFICE.

RICHARD FORTEMPS, OF COLOGNE, GERMANY.

DESIGN FOR PLATE-GLASS.

No. 38,713.

Specification for Design.

Patented July 30, 1907.

Application filed May 13, 1907. Serial No. 373,518. Term of patent 3½ years.

To all whom it may concern:

Be it known that I, RICHARD FORTEMPS, a subject of the King of Prussia, German Emperor, residing at Cologne, in the Province of the Rhine, Kingdom of Prussia, German Empire, have invented a new, original, and ornamental Design for Plate-Glass, of which the following is a specification, reference being had to the accompanying drawings, forming part thereof.

The accompanying drawing is an elevation showing the design of the plate glass.

I claim

The ornamental design for plate glass, as shown.

RICHARD FORTEMPS.
